UNITED STATES PATENT OFFICE

WILLIAM EUGENE ENDREZZE, OF BUTTE, MONTANA

COMPOUND AGITATOR FOR FLOTATION SEPARATORS

Application filed August 8, 1927. Serial No. 211,464.

This invention relates to agitators for separating machines of the flotation type and adapted particularly for use in connection with the separation of minerals and has for a principal object to provide a compound mechanical and air agitator for use in the separation process.

Another object is to arrange a stationary air agitator for use in connection with machines of this character and which may be used either independently of or in conjunction with a mechanical agitator, said stationary air agitator comprising an air chamber having its walls formed of foraminous material through which the air may be discharged into the body of mineral to be treated and arranging the walls of said compartment in a vertical position so as to prevent the collection of particles of the mineral thereon and thus insure the continuous and free passage of air through the walls of such compartment.

A further object is to provide a mechanical agitator adapted to be used in combination with the stationary air agitator and including a rotatably mounted impelling device arranged adjacent the intake ports of the separator and adapted to force the material received therein against reflecting plates whereby to distribute the material in an upward direction against each side of the stationary air agitator for treatment thereby.

A still further object is to provide an apparatus of this character of simple and practical construction, efficient and reliable in performance, which is capable of being maintained in operative position over a prolonged period without necessitating the care of an attendant, which may be readily installed in operative position upon conventional types of separators without necessitating any changes or alterations in the construction thereof, which is relatively inexpensive to manufacture, and otherwise well adapted for the purposes for which the same is intended.

Other objects and advantages reside in the special construction and combination of the various elements forming the invention, reference being had to the accompanying drawing, wherein:—

Figure 1 is a side elevational view with parts shown in section of a separating machine equipped with a plurality of air agitators constructed in accordance with one form of my invention.

Figure 2 is a vertical transverse sectional view therethrough.

Figure 3 is a longitudinal vertical sectional view through another type of separator, and illustrating the use of my combined mechanical and air agitator therewith.

Figure 4 is a transverse vertical sectional view thereof.

Figure 5 is an elevational view of the combined mechanical and air agitator.

Figure 6 is a plan view of the impeller.

Figure 7 is a plan view of one of the air agitator compartments.

Figure 8 is a side elevational view thereof.

Fig. 9 is a vertical sectional view through one of the single air agitator compartments showing the manner of retaining the canvas or other fabric around the sides thereof, and,

Figure 10 is a side elevational view thereof showing the clamping members for the upper and lower edges of the canvas.

Referring now to the drawings in detail, Figure 1 represents a mineral separation apparatus of the flotation type of a simple construction comprising a substantially rectangular separator container indicated generally at 5, open at its top, with a pulp intake launder 6 arranged at one end and a pulp discharge box 7 and pulp discharge junction box 8 arranged at its opposite end with froth launders 9 formed at each side thereof and extending longitudinally of the separator. Upon the bottom of the container 10 I arrange a plurality of stationary air agitators 11, arranged longitudinally of the container and extending from end to end therein, said agitators comprising a rectangular frame 12 as indicated in Figure 9 of the drawing, including the rigid top and bottom sections indicated at 13 and 14 respectively supported by vertical braces 15 and about the side walls of which is arranged a section of canvas 16 or like foraminous material and secured on the frame at its upper and lower edges by a clamp member 17. The

edges of the plates 13 and 14 are provided with horizontal grooves 18 with the clamps 17 having their inner faces provided with ribs 19 adapted to seat within said grooves whereby to force the upper and lower edges of the canvas 16 within the same whereby to securely retain the canvas in a vertical position at the sides of the agitator. The supports 15 are also provided with threaded sockets 20 at suitable spaced intervals and adapted to threadedly receive screws 21 arranged to secure strips 22 extending vertically on the outer walls of the canvas as illustrated in Figure 5.

As more clearly illustrated in Figure 2 of the drawing the base of the container 5 is formed into a substantially trough shaped compartment 23, the air agitators 11 being arranged in a row extending longitudinally along the base thereof. The top of the agitator carries a hood 24 of a peaked formation adapted to prevent the collection of sediment or particles of the mineral thereon. An air feed pipe 25 is disposed beneath the separator having air intake pipe sections 26 communicating with each of the agitators 11. The feed pipe is provided with suitable air valve regulating keys 27.

In the operation of this feature of the invention, the mineral pulp is fed through the pulp inlet 6 into the trough 23 of the separator at the base of which the same comes into contact with the air discharged through the air agitators 11. This air being discharged into the mass of material forms air bubbles through which the reagent oils and minerals within the pulp clings and as the same rises to the surface through the buoyancy of the air a froth is formed which overflows into the trough launders 9 where it is sprayed to break the air bubbles and conveyed through discharge pipes 28 to a suitable receptacle for washing and separating the mineral from the water after which the mineral is dried for shipment to the refinery.

In addition to the air agitator for use in separating the mineral, I may also employ the use of a mechanical agitating device comprising an impeller 29 mounted for rotation beneath the air agitator upon a vertically extending shaft 30 extending to the upper part of the separator above which the same is suitably supported by frames 31 and bearing brackets 32 and provided with a pulley wheel 33 by means of which the shaft is operated through a suitable source of power. The impeller 29 is of an annular formation having a plurality of blades 34 arranged radially therein, the impeller being open at its upper and lower sides and also having ports 35 extending horizontally through the walls thereof. Above the impeller in spaced relation therefrom is a deflector plate 36 arranged for rotation upon the shaft together with the impeller and against the under side

of which the material from the blades 34 is discharged and deflected outwardly therefrom.

When employing the use of a combined mechanical and air agitator of this type, the pulp is fed into the trough shaped compartment 23 of the separator through a feed pipe 37 at the base thereof and directly beneath the agitator. The pulp is thoroughly agitated by the blades 34 in driving the same against the deflector 36 and throwing the same outwardly therefrom as the same moves upwardly past the sides of the air agitator 11. In this manner a double agitating force is directed against the pulp before the froth is formed for discharging in the froth launders 9.

In this form of the invention the air agitator 11 is held in a suspended position within the separator by means of the shaft housing 38 through which the shaft 30 extends, said shaft also extending vertically through the air agitator frame 11 for operating the impeller 29 beneath the same, the upper end of the shaft housing 38 being formed with flanges 40 for attaching to one of the upper frame members 31. Air feed pipes 41 extend through the upper end of the air agitator 11 to within the same and communicating with the air supply pipe 42 arranged above the separator. In this form of the invention the upper and lower ends of the air agitator 43 and 44 respectively are of a cone-shaped formation extending outwardly at each end whereby to prevent the accumulation of sediment of mineral particles thereon. The frame for the air agitator is also of cylindrical formation so as to enable the pulp to travel upwardly against the sides thereof in a more uniform and even manner.

As shown in Figures 7 and 8 of the drawing the air agitator may be formed into a plurality of compartments when used in connection with a separator of the type as shown in Figure 1. This form of the air agitator may comprise any suitable number of compartments, the present embodiment of the invention disclosing an agitator formed of three of such compartments each having an air feed pipe 45 extending through the base thereof for discharging air through the vertical walls 46 which are formed of sections of canvas or like foraminous material in accordance with the construction thereof as heretofore explained. The upper and lower clamping members 47 may be formed in sections and connected to each other at their ends as at 48.

The provision of an air agitator of this character provides more area for the face thereof through which the air is discharged into the mass of pulp, thus permitting more air to be used during the separating process. As the sides of the agitator through which the air is discharged is in a vertical posi-

tion, the heavy condensate cannot settle thereon causing uneven agitation or obstructing the passage of the air from the agitator. The device therefore requires very little attention during the operation thereof and enables the separation to proceed in a more expeditious and economical manner.

It is obvious that the invention is susceptible of various changes in the construction and combination of the various elements forming the same, without departing from the spirit or scope of the appended claims, and I accordingly claim all such forms of the device to which I am entitled.

15 I claim:—

1. In combination, a flotation agitator supporting frame having a covering of foraminous material thereon forming an enclosed air compartment therein, means for supplying air within the compartment for discharge through the walls thereof, said walls being arranged in a vertical position and a mechanically operated agitator carried at the lower end of the frame and adapted to urge the material under agitation upwardly past and outside of the walls of the compartment.

2. In combination, a separator comprising a container, pulp intake and discharge means therefor, and an agitator for the pulp comprising a frame having a covering of foraminous material at each vertical side thereof, air supply means communicating therewith adapted to discharge the air through the sides thereof into the pulp, an impeller rotatably mounted beneath said frame, a deflector interposed between the impeller and the frame against which to force the pulp for deflecting the same outwardly and upwardly past the sides of the frame and a rotatable shaft operatively connecting said impeller.

40 3. An air discharge container for flotation separators comprising a frame composed of upper and lower frame members, vertical supports therefor adapted to secure the members in spaced relation, the outer edge of said members having a horizontal groove formed therein, a covering of foraminous material for this frame, a covering retaining band disposed in clamping position about the cover at the edges of said member, and said band provided with a rib adapted to force a portion of the cover material into said groove, and means for feeding air into said container for discharge through the walls thereof.

55 4. An air discharge container for flotation separators comprising a frame composed of upper and lower frame members, vertical supports therefor adapted to secure the members in spaced relation, the outer edge of said members having a horizontal groove formed therein, a covering of foraminous material for the frame, a cover retaining band disposed in clamping position about the cover at the edges of said members, and said band

provided with a rib adapted to force a portion of the cover material into said groove, means for feeding air into said container for discharge through the walls thereof, and means for supporting a mechanically operated agitator beneath the frame member and arranged to direct a current of fluid upwardly past the outside of the walls of said container.

5. A flotation device, comprising a frame composed of upper and lower frame members, vertical supports therefor adapted to secure said members in spaced relation, a covering of foraminous material disposed about said frame members forming an enclosed air compartment therein having the outer surface of its walls exposed to the mineral under treatment and means for feeding air into said compartment for discharge through the vertical side walls thereof and operable to maintain said vertical walls free from the accumulation of mineral thereon.

6. A flotation device comprising a pulp container, a rectangular frame composed of upper and lower frame members, vertical supports therefor adapted to secure the members in spaced relation, a covering of foraminous material about said frame forming an enclosed air compartment therein, said compartment being supported in spaced relation from the walls and bottom of said pulp container and extending longitudinally from end to end therein, a peaked hood at the top of said compartment having its inclined surfaces arranged whereby to prevent accumulation of sediment thereon, said compartment being divided into a plurality of individual air chambers and means for feeding air into each of said chambers for discharge through the foraminous walls thereof.

7. A flotation device comprising a frame of cylindrical formation composed of upper and lower annular frame members, vertical supports therefor adapted to secure the members in spaced relation, a central vertical support of tubular construction providing a shaft housing, a shaft extending therethrough, an agitator mounted at its lower end, a covering of foraminous material about said frame forming an enclosed air compartment therein, a cone shaped cover for the upper and lower portions of the compartment and means for feeding air into said compartment for discharge through the foraminous material forming the vertical walls thereof.

8. A rotary agitator for flotation machines comprising a horizontally supported annular member, port holes extending horizontally through the sides thereof, radially disposed blades terminating at said port holes and having their surfaces disposed angularly from a horizontal plane, a deflector plate disposed above said blade in spaced relation

therefrom and connected for rotation therewith and a drive shaft forming suspension means for the agitator within said machine.

9. In combination, an enclosed air discharge container having vertical side walls formed of foraminous material, means for suspending said air container submerged in a tank of pulp, a vertical drive shaft extending through said air container, an impeller attached at its lower end for agitating the pulp beneath the air container and means for feeding air into said air container for discharge through the vertical walls thereof whereby to aerate the pulp above said impeller.
- 10.
- 11.
- 12.
- 13.
- 14.
- 15.

In testimony whereof I affix my signature.

WILLIAM EUGENE ENDREZZE.
